UNITED STATES PATENT OFFICE.

THOMAS EASTWOOD, OF WALSDEN, ENGLAND.

SPINNING-MACHINE.

SPECIFICATION forming part of Letters Patent No. 655,698, dated August 14, 1900.

Application filed February 9, 1898. Serial No. 669,675. (No model.)

To all whom it may concern:

Be it known that I, THOMAS EASTWOOD, a subject of the Queen of Great Britain, residing at Walsden, in the county of Lancaster, 5 England, have invented certain new and useful Improvements in Spinning-Machines, of which the following is a full and complete specification, such as will enable those skilled in the art to which it appertains to make and 10 use the same.

This invention relates to improvements in yarn-spinning machines; and it has for its object to provide for the general efficiency and utility of this class of machines.

15 The invention consists in the features of construction and combination of parts herein-after fully described and specifically claimed.

The invention is fully disclosed in the following specification, of which the accompanying 20 drawings form a part, in which the separate parts of my improvement are designated by the same letters of reference in each of the views, and in which—

Figure 1 is an end elevation of a spinning-machine constructed in accordance with this 25 invention. Fig. 2 is a front elevation of a portion of the machine. Fig. 3 is a central vertical section, on an enlarged scale, of the twisting mechanism. Fig. 4 is a similar detail view of the base supporting the twister-sleeve; and Fig. 5, a plan view of a portion of Fig. 1, showing the cop-building mechanism upon an enlarged scale.

The invention is designed to overcome and 30 obviate the variation of the extent to which the yarn is twisted in spinning and to furnish mechanism for giving an even and constant twist. The invention is applicable to ring-frame machines, in which heretofore, as far 35 as I am informed, the spindle is driven and the traveler "dragged" after it, causing a variation on the amount of twist on the yarn by reason of the varying diameter of the surface upon which the winding takes place. It is 40 necessary for the traveler to lag to a certain extent, while the angle at which the yarn is held when winding on a small diameter gives an excessive strain thereto. To obviate these objections and to furnish an efficient 45 and practical machine, I provide the construction shown in the accompanying drawings and which will now be described in de-

tail. As the general structural characteristics are the same as those in machines in general use, the general arrangement and operation will be clearly understood. 55

In accordance with the principle of this invention the sleeve G is positively driven, while the spindle S can be driven by a differential speed motion or allowed to lag by means of 60 a "drag." The main driving-shaft A is suitably geared to the delivery-rollers R, as shown, and extends inside of the framework and is provided with a toothed wheel A' and a swing C', the other end of the latter being 65 attached to the shaft D' of the roller D. The shaft D' is provided with a gear-wheel B and is driven by the main shaft by the intermediate gearing shown. The said rollers D and D'' are mounted in bearings on a rail D³, 70 while from the ends of the rails D³ arms D² extend upwardly and support the rails D⁴, carrying the twister-sleeves G. The particular construction comprises a collar F, secured within an opening in the rail and provided externally near its ends with flanges forming ball-races, while the twister-sleeve surrounds the same and has corresponding ball-races to receive the balls, as shown. The collar F is provided with an annular flange F' upon the 80 upper portion thereof, and the flange F' is detachably secured to the collar F by a screw-thread, as shown in Figs. 3 and 4. The sleeve G has an exterior groove to receive the band or tape a, by means of which it is rotated 85 from the rollers D. At the upper end of the sleeve G is an eye or guide G³, through which the yarn passes and by means of which the twist is imparted thereto.

The yarn is guided to the spindle S^x or tube 90 or bobbin, as the case may be, by means of the above-described framework, carrying the revolving twister-sleeve G, which has an upright reciprocatory movement derived from the lifter motion, differing from the usual 95 lifter motion in that a rack-and-pinion gearing is employed instead of the upright poker.

The bobbins are placed in the usual reel, and the yarn passes through the delivery-rolls R, as is usual. The yarn passes from 100 the rollers R through the eyes W, and thence to the guide-eyes G³ of the twister, which is conveniently a small hooked piece of metal, as shown. The rail D³ is provided with de-

pending gear-racks R R', that intermesh with the gear-segments H H' upon the rock-shaft H'', and the latter receives its motion from the mechanism of the lifter or builder. This latter mechanism I preferably construct as follows: A lever-arm L is pivotally mounted at one end on the stud L', secured to the frame of the machine at the end thereof. The lever L is so mounted as to be capable of vertical oscillation. At a point near the outer end of the lever L, in the upper portion thereof, is mounted a roller L², and above the roller L² is mounted a shaft M', which bears a cam M, and the shaft M' is operatively connected with the main shaft A in any suitable manner and is revolved thereby at a predetermined speed, and the cam M operates in connection with the roller L² to intermittently depress the lever L. Mounted upon the lever L, at the outer end thereof, is a frame N, (best shown in Fig. 5,) and journaled in said frame N, transversely thereof, as at O', is a shaft O, and the shaft O bears within said frame a fixed worm J' and exteriorly of said frame a fixed ratchet-wheel K'. A pawl-arm K³ is provided out of its central point of gravity with a collar K⁴, by which it is mounted pivotally upon the shaft O, exteriorly of the frame N, and the frame N is provided with a lug or stop N', under which the shorter and inner end portion K⁵ of the pawl-arm K³ normally rests. A pawl K² is pivotally connected with the longer and outer end portion K⁶ of the pawl-arm K³ and is adapted to operate in connection with the ratchet-wheel K'. A stop R^X is secured to the frame of the machine beneath the outer end K⁶ of the pawl-arm K³, and said outer end K⁶ is adapted to come in contact with said stop R^X when the lever L and frame N are depressed by the cam M. A shaft S is journaled in the frame N, as at S' S', longitudinally thereof, and is provided with a gear-wheel K⁷, correspondingly threaded to the worm J' and in mesh therewith. The shaft S also bears a pulley J, keyed thereto. Parallelly and similarly mounted to the shaft S is another shaft T, which bears a bevel-gear T', keyed thereto, and the inner end of the shaft O is provided with a corresponding fixed bevel-gear O², which operates in connection with the bevel-gear T'. The shaft T extends exteriorly of the frame N and is squared, as at T², to receive a crank. A chain I' is secured to the chain-pulley J and extends upwardly and is secured to a chain-pulley I, revolvably mounted upon a short shaft I², secured to the frame of the machine. Another similar chain-pulley I³ is revolvably mounted upon the outer end of the shaft I² and is locked to the pulley I in any suitable manner, as by a sleeve I⁴. Connected with the pulley I³ is a chain H³, and the chain H³ is secured at the other end to the lever H² of the gear-segment H', as previously described.

The operation of this portion of my im-

provement will be readily understood. The cam M when revolved depresses the lever L and the frame N, bringing the end portion K⁶ of the pawl-arm K³ into contact with the stop R^X, and as the lever L continues to descend the said end portion K⁶ will be held stationary, thus in effect revolving the pawl-arm K³ about the shaft O, and the pawl K² will force around the ratchet-wheel K', revolving the shaft O, the worm J', the gear-wheel K⁷, the chain-pulley J, and drawing down the chain I', revolving the chain-pulleys I and I³ and winding up the chain H³ upon the chain-pulley I³, thus revolving the shaft H'' and operating the gears H H' to raise the gear-racks R and R' and the rail D³. The gearing of the rail D³ and connections will reversely operate the lever L and connections to such an extent as allowed by the conformation of the cam M; but as at each depression of the lever L an added portion of the chain I' is wound upon the chain-pulley J the rail D³ is intermittently raised throughout the play of the gear-racks R'. When it is desired to lower the rail D³, a crank may be applied to the end T² of the shaft T, the pawl K² removed from the ratchet-wheel K', and the shaft O allowed to revolve, so as to unwind the chain I' from the chain-pulley J. The said twister-sleeve is provided at its lower end with a groove or slot G' to receive a brake G², whereby the movement of the twister may be arrested, for instance, when necessary to piece a broken end.

The chief advantages which are claimed for this machine are that there is a constant number of turns in the yarn and also that soft-twisted yarn, such as wofts, can be efficiently spun.

Having fully described my invention, I claim as new and desire to secure by Letters Patent—

1. In a spinning-machine, a main shaft A, a stationary frame, a vertically-movable support mounted therein, rack-bars connected with said movable support, a shaft H'' journaled in said frame, segmental gears mounted on said shaft and operating in connection with said rack-bars, a lever connected with said shaft and devices for intermittently depressing said lever to intermittently raise said rack-bars, comprising a lever-arm pivoted at its inner end to said stationary frame and provided at its outer end with a frame, a shaft O mounted therein, a worm and a ratchet-wheel rigidly mounted on said shaft O, a pawl-arm pivotally mounted on said shaft O and bearing a pawl adapted to operate in connection with said ratchet-wheel, a stop on said lever-arm against the inner and lighter end of which said pawl-arm normally rests, and a stop on said stationary frame which the outer end portion of said pawl is adapted to engage to force said pawl into operative engagement with said ratchet-wheel, said shaft H'' in said frame being flexibly and operatively connected with said lever and a cam

operated by said main shaft and operating in connection with said lever-arm to intermittently depress the same, substantially as shown and described.

5 2. In a spinning-machine, a main shaft A, a stationary frame, a vertically-movable support mounted therein, rack-bars connected with said movable support, a shaft H" journaled in said frame, segmental gears mounted on said shaft and operating in connection with said rack-bars, a lever connected with said shaft and devices for intermittently depressing said lever to intermittently raise said rack-bars, comprising a lever-arm pivoted at its inner end to said stationary frame and provided at its outer end with a frame, a shaft O mounted therein, a worm and a ratchet-wheel rigidly mounted on said shaft, a pawl-arm pivotally mounted on said shaft O and bearing a pawl adapted to operate in connection with said ratchet-wheel, a stop on said lever-arm against the inner and lighter end of which said pawl-arm normally rests, and a stop on said stationary frame which the outer end portion of said pawl is adapted to engage to force said pawl into operative engagement with said ratchet-wheel, said shaft

H" in said frame being flexibly and operatively connected with said lever, a cam operated by said main shaft, and operating in connection with said lever-arm to intermittently depress the same, a supplemental shaft S mounted at right angles to said shaft and provided with a gear-wheel in operative connection with said worm on said shaft, a chain-pulley on said supplemental shaft and a chain secured to and adapted to be wound thereon in connection with said lever, a cone-gear rigidly mounted upon said shaft H" in said frame which is secured to said lever-arm, a second supplemental shaft T mounted in said frame and provided with a cone-gear, in operative connection with said other cone-gear, and devices for turning said second supplemental shaft T to unwind said chain from said chain-pulley, substantially as shown and described.

In testimony that I claim the foregoing as my invention I have signed my name, in presence of the subscribing witnesses, this 29th day of February, 1898.

THOMAS EASTWOOD.
